SEPARABLE FASTENER

Gideon Sundback, Meadville, Pa., assignor to
 Hookless Fastener Company, Meadville, Pa., a
 corporation of Pennsylvania

Application September 1, 1933, Serial No. 687,802

4 Claims. (Cl. 24—205)

This invention relates to separable fasteners and particularly to the beaded edge construction of flexible stringers for such fasteners. This application is in part a continuation of my earlier 5 application, Ser. No. 402,729, filed October 26, 1929, now Patent No. 1,949,889, dated March 6, 1934.

The principal object of the present invention is to provide an improved beaded edge construction 10 which will not require additional operations for attaching cords or the like to a flat tape, or a complicated weaving operation to weave a cord in the edge of the tape.

According to the present invention the beaded 15 edge or shoulder is formed by folding up the edge of the flexible strip which is usually a fabric tape. In order to get sufficient thickness for the shoulder it is preferable to have at least three plies of fabric.

20 In the accompanying drawing I have shown for purposes of illustration, three embodiments which my invention may assume in practice. In this drawing:

Fig. 1 illustrates generally a fastener of the 25 type to which my invention relates;

Fig. 2 shows in cross-section one embodiment of the stringer construction; and

Figs. 3 and 4 illustrate in cross-section two other embodiments.

30 The separable fastener shown in Fig. 1 comprises two flexible stringers or tapes, having single ply base portions 5 and beaded edges 6 and fastener elements 7 arranged in uniformly spaced relation and clamped around the beaded 35 edges 6. The fastener elements are brought into engaging relation by means of a slider 8 which is actuated by a pull tab 9. The construction and operation of the fastener elements and slider are well-known and will not be further 40 described.

Referring to Fig. 2, each fastener element 7 has clamping jaws 10 which engage around the beaded edge. In this instance, the tapes are folded over at 11 and reversely folded under the 45 first fold so that the edge 12 extends nearly to the first fold. This provides a shoulder on one side and in order to form a shoulder on the other side, a separate cord or strip 13 is arranged in proper position. This additional strip can be guided into the machine which clamps on the fastener elements and no additional attaching means is required.

It is likewise true that in this embodiment and the other embodiments, the folded edge does not 55 need to be held together by sewing or other means since the folder can be arranged very close to the mechanism which clamps on the fastener elements.

In Fig. 3, the tape is first folded back upon 60 itself at 14 and it is reversely folded at 15 back

around the first fold to the opposite side of the tape and the edge 16 is turned under so as to provide two additional plies on each side of the tape, making a five ply beaded edge. This structure is symmetrical and in cases where it can be folded without difficulty it would be a desirable construction. However, the structure shown in Fig. 4 is easier to control accurately in the manufacture of fasteners, and it is believed to be the preferred construction. In this case, the tape is first folded at 17 and reversely folded at 18 back around the first fold so that the edge 19 overlaps on the opposite side to provide a single ply on that side. This results in a four ply section which is of sufficient thickness to hold the clamping portions of the fastener elements.

While I have shown and described in this application three embodiments which my invention may assume in practice, it will be understood 20 that these embodiments are merely for the purposes of illustration and description and that other forms may be devised within the scope of my invention as defined in the appended claims.

What I claim as my invention is:

1. A stringer for separable fasteners comprising a single ply fabric tape folded along one edge back upon itself and having the edge turned under said folded portion to provide a shoulder on one side of the tape, and means 30 forming a shoulder on the opposite side of said tape, said shoulders constituting means to receive the clamping portions of fastener elements.

2. A stringer for separable interlocking fasteners comprising a flexible strip having its edge 35 folded back upon itself and reversely folded back around said first fold so that the edge of the tape lies on the opposite side from the first fold to provide a four ply beaded edge for receiving the clamping portions of fastener elements.

3. A stringer for separable fasteners of the class described, comprising an elongated narrow fabric tape with a single ply base portion and a beaded edge providing shoulders on both sides of the plane of said tape, said beaded edge being 45 relatively narrow so that it is adapted to be completely embraced by the jaws of the separable fastener elements, said beaded edge consisting of folds of the tape to provide the shoulder on one side of the plane of the base portion, and means forming the shoulder on the opposite side of the plane of said base portion.

4. A stringer for separable fasteners comprising a fabric tape having a single ply base portion and a beaded edge providing shoulders on 55 opposite sides of the plane of the base portion and comprising at least four plies of tape folded upon one another, the extreme edge of the tape being included in the beaded edge.
